UNITED STATES PATENT OFFICE.

RALPH L. HINMAN, OF ONEIDA, NEW YORK, ASSIGNOR TO HINMAN MILKING MACHINE COMPANY INC., OF ONEIDA, NEW YORK, A CORPORATION OF NEW YORK.

DRIVE MECHANISM FOR MILKING MACHINES.

Application filed February 10, 1927. Serial No. 167,210.

This invention relates to new and improved drive mechanism for milking machines.

The main object of the invention is to provide a drive mechanism that can be readily and easily attached as a unit to any ordinary construction of stanchion without the provision of additional parts, structure and equipment.

A further object is to provide a drive mechanism that will operate efficiently and for long periods of time in actuating a drive rod for a plurality of pumps in a regular and uniform manner.

Other objects and advantages relate to the details of the structure and the form and relation of the parts thereof, all as will more fully appear from the following description taken in connection with the accompanying drawings, in which:

Figure 1 is an elevation of the mechanism secured to an ordinary form of stanchion structure.

Figure 2 is a section on line 2—2, Figure 1.

Figure 3 is a section on line 3—3, Figure 2.

Figure 4 is a longitudinal section through the mechanism.

Figure 5 is a section on line 5—5, Figure 1.

Figure 6 is a section on line 6—6, Figure 1.

Figure 7 is a view partially in section of the means for securing the connecting rod to the chain or belt.

The structure as shown comprises two spaced brackets —1— of similar form and shape. Each of these brackets —1— comprises a plate —2— formed with recesses —3— in its upper and lower edges for the reception of bolts —4— by means of which the bracket is secured to a stanchion frame —5—.

As best shown in Figure 6, this back plate —2— is preferably formed with a concavity in its rear surface to adapt the bracket for more efficient securement to a stanchion frame formed of pipe or cylindrical bars, as indicated in dotted lines, Figure 6.

Each of the brackets —1— also includes a central flange —6— that extends forwardly from the central portion of the bracket and preferably projects slightly above and slightly below the plate —2—, the lower portion of the flange —6— being recessed at —7— for the reception of a milking machine drive rod —8—. An angle bar —9— of a length sufficient to extend between the flanges —6— is provided and one wall —10— of the angle bar rests upon the upper surface of the

flanges —6— and is secured thereto in any suitable manner as by screws —11—.

The other wall —12— of the angle bar extends vertically downward along the front of the flanges —6— and is secured to the flanges —6— in any suitable manner, as by bolts —13—.

In this manner a rigid framework is formed and which may be secured to any stanchion frame by the mere use of the bolts —4—, the drive rod sliding in the recesses —7— in the lower forward portion of the flanges —6—.

For the purpose of reciprocating the rod —8— this rod has a bracket —14— rigidly secured to it in any suitable manner as by bolts —15—, the bracket including a portion which projects upwardly between the stanchion frame —5— and the wall —12— of the angle bar —9—. One end of a connecting rod —16— is pivotally secured to the upper end of the bracket —14— and the opposite end of the connecting rod —16— is preferably connected to the chain or belt —17— by means of a pivot pin —18—, which pin in this illustration also forms the means for pivotally connecting two links of the chain —17—.

The chain —17— moves over a pair of spur gears —19— and —20— respectively. The gear —19— is splined to a shaft —21— which extends outwardly through the wall —12— and through a sleeve —22— mounted in a bearing —23— secured to the wall —12— in any suitable manner, as by screws —24—. A pulley —25— is mounted upon the outer end of the shaft —21— and is secured to the shaft in any suitable manner, as by a set screw —26—, the pulley having its hub in contact with the bearing —23— and thereby holding flange —27— on the shaft in contact with the inner side of the bearing. For driving the chain, the pulley —25— is belted to a pulley —50— on the armature shaft of a motor —51— bolted to the wall —10— of the angle bar —9—.

The gear —20— in a somewhat similar manner is mounted upon a stub shaft —29— extending outwardly through the wall —12— and through a bushing —30— mounted in a sleeve —31— journaled in a bearing —32— secured to the wall —12— in any suitable manner as by screws —33—. The flange —34— on the shaft —29— is held against the sleeve —31— by a cap plate —35— secured to the end of the shaft, as by screw —36—, the outer portion of the cap plate

resting in contact with the outer end of the sleeve —31—. Preferably, as best illustrated in Figure 3, the bushing —30— is eccentrically mounted in the sleeve —31— so that by rotation of the sleeve —31— the gear —20— can be moved toward and from the gear —19—, thereby providing an adjustment for maintaining the chain or belt —17— tight.

10 The drive rod —8— in addition to its support in the recesses —7— is slidably secured to the stanchion frame in any usual manner, as by guides —40—. The pumps —41— may be supported in any usual manner and have their piston rods —42— removably secured to the drive rod —8— in any usual manner, and altho I have shown and described a specific structure as constituting a perhaps preferred embodiment of the invention, I do not desire to restrict myself to the details of form, arrangement or relation of the parts thereof, as various changes and modifications may be made within the scope of the appended claims.

25 I claim:

1. A drive mechanism for milking machines comprising a pair of spaced brackets having forwardly projecting flanges, means for securing the brackets to a stanchion frame, an angle bar secured at its opposite ends to respective flanges and having one of its walls substantially horizontally disposed and extending across the upper ends of the flanges and its other wall substantially vertically disposed and extending downwardly along the front edge of the flanges, a pair of rotary members supported from said angle bar, a belt mounted on the gears for movement therewith, a drive rod and a connecting rod actuated by the belt to reciprocate the drive rod.

2. A drive mechanism for milking machines comprising a pair of spaced brackets having forwardly projecting flanges, means for securing the brackets to a stanchion frame, an angle bar secured at its opposite ends to respective flanges and having one of its walls substantially horizontally disposed and extending across the upper ends of the flanges and its other wall substantially vertically disposed and extending downwardly along the front edge of the flanges, a pair of rotary members supported from said angle bar, a belt mounted on the gears for movement therewith, a drive rod and a connecting rod actuated by the belt to reciprocate the drive rod.

2. A drive mechanism for milking machines comprising a pair of spaced brackets having forwardly projecting flanges, means for securing the brackets to a stanchion frame, an angle bar secured at its opposite ends to respective flanges and having one of its walls substantially horizontally disposed and extending across the upper ends of the flanges and its other wall substantially vertically disposed and extending downwardly along the front edge of the flanges, a pair of rotary members supported from said angle bar, a belt mounted on the gears for movement therewith, a drive rod and a connecting rod actuated by the belt to reciprocate the drive rod, and means for adjusting one of the rotary members to tension the belt.

3. A drive mechanism for milking machines comprising a pair of spaced brackets having bolt-receiving openings, each bracket formed with a forwardly projecting flange having a recess in its forward edge, a drive rod mounted in said recesses, an angle bar extending between and secured to the flanges, a pair of gears journaled on the angle bar, a chain belt moving with the gears, a bracket on the drive rod, a connecting rod having one end pivotally secured to said bracket on the drive rod and its other end connected to the chain belt, and a motor mounted on the angle bar and connected to drive one of said gears for reciprocating the drive rod.

In witness whereof I have hereunto set my hand this 4th day of February, 1927.

RALPH L. HINMAN
